CIRCUIT BREAKERS

Howard E. Reichert and Gerald J. Freese, Beaver, Pa., assignors to Westinghouse Electric Corporation, East Pittsburgh, Pa., a corporation of Pennsylvania

Application July 30, 1952, Serial No. 301,692

6 Claims. (Cl. 200—168)

This invention relates to electrical devices in general and more particularly to terminal constructions for electrical devices such as circuit breakers.

An object of the invention is to provide a circuit interrupter having exposed terminals for connecting the circuit interrupters in an electrical circuit with a terminal cover acting as a guard for preventing accidental contact with a live terminal.

Another object of the invention is to provide a circuit interrupter having exposed terminals with a protective cover for the terminals which requires no separate means for fastening it in place.

Another object of the invention is to provide a circuit interrupter having exposed terminals with a snap-on terminal cover formed from a flat sheet of insulating material and which requires no separate means for holding the cover in place on the housing of the interrupter.

The invention, both as to structure and operation together with additional objects and advantages thereof, will be best understood from the following detailed description thereof when read in connection with the accompanying drawing.

In said drawing:

Figure 1 is a perspective view showing one end portion of a circuit interrupter housing having exposed terminals and showing the protective cover for the terminals partly broken away for clearness.

Fig. 2 is a view showing the protective cover before it is mounted in place on the base of the interrupter.

Fig. 3 is a perspective view of the protective cover.

Referring to Fig. 1 of the drawing, the circuit breaker 9, a portion of which is shown in Fig. 1, comprises a housing including a base 11 and a cover 13 secured to the base by means of screws 15 (only one being shown). The circuit breaker may be of the type shown in U. S. Patent No. 2,458,151, issued to Hiller D. Dorfman and Gerald J. Freese January 4, 1949, and assigned to the assignee of the instant application. Only a portion of the breaker housing is shown and described herein. The cover 13 may be sealed to the base by a sealing compound 17 poured over the heads of the screws 15 to prevent tampering with the breaker mechanism and changing the calibration of the breaker.

The base 11 of the breaker is longer than the cover 13 providing projecting end portions 19, (only one being shown), for supporting the breaker terminals.

The projecting end portions of the base 11 have one or more recesses 21 therein, in each of which is mounted a terminal 23. The raised or projecting portions 25 on the projecting end portions 19 of the base 11 between the terminals 23 and at the sides of the outer terminals form insulating barriers between adjacent terminals.

The terminals 23 are rectangular in shape and are mounted on the projecting ends 19 of the base 11 in the recesses 21 and are secured to conducting terminal strips 24, (only the ends being shown), for connecting the breaker in an electrical circuit. The terminals 23 are provided with terminal screws 26 which threadedly en-

2

gage an opening through the conducting strip 24 and the upper portion of the terminal 23. Pivotedly mounted on the lower ends of each of the screws 26 is a clamping member 28 so that upon rotation of the screw 26 the clamping member will move up and down in the terminal thus providing means whereby the end of a conducting cable 30 may be securely clamped to the terminal 23. By having the electrical terminals 23 on the end portions 19 of the base 11 which project beyond the ends of the cover 13, the electrical connections may be made to the terminals without breaking the seal and removing the cover 13.

It is, at times, necessary to make connections to the breaker terminals from an energized bus. Under such conditions, particularly when the circuit breakers are mounted end to end in a panelboard or switchboard, and because of the exposed terminals of the breakers, accidental contact may be made simultaneously with adjacent terminals. To prevent such accidents and possible serious or even fatal injury to the person working on the circuit breakers, there is provided a snap-on protective cover or guard for the terminals of the breaker.

The protective cover 27 is made from a flat strip of insulating material in the shape shown in Fig. 2. The blank shown in Fig. 2 is cut from a sheet of insulating material having some resiliency such, for example, as hard fiber or a material having a cloth or fibrous base impregnated with a phenolic resin. The cover 27 has projections 29 along the bottom (Fig. 2) and projections 31 along the top. The cover is also provided with a top portion 38 having end portions 33. The blank is formed or bent along the line 37 as shown in Fig. 3 so that the projections 29 make a right or slightly obtuse angle with the main top portion 38 when the cover is removed from the breaker and is in its unstressed condition. The projections 29 are adapted to fit into slots 35 in the recesses 21 and the projections 31 are adapted to be snapped into the recesses 21 under the end of breaker cover 13 as at 36 (Fig. 1).

In order to place the protective cover 27 in position on the projecting end 19 of the base 11 the projections 29 are inserted downwardly in the recesses 21 so that the projections 29 enter the slots 35 defined by the ends of the conducting strips 24 and the base 11, and the short projections 31 are snapped into the recesses 21 under the breaker cover 13. The downwardly projecting portions 29 are then bent at a right angle to the top portion 38 against the resiliency of the material which then holds the cover in position. When placed in position on the projecting end of the base 11 the main body of the terminal cover rests on the barriers 25 covering the tops of the recesses 21 and the projections 29 of the terminal cover close the ends of the recesses 21, thus completely enclosing the upper part of the terminals.

55 The provision of the protective cover eliminates or greatly reduces the possibility of a person's hand accidentally touching a live terminal, or of bringing a tool into simultaneous contact with the terminals of adjacent phases of the circuit. The protective cover is placed in 60 position on the base without the use of tools and held in position without any separate fastening means such as screws or springs.

Having described the invention in accordance with the provisions of the patent statutes, it is to be understood 65 that various changes and modifications may be made in the structural details and arrangement of parts thereof without departing from some of the essential features of the invention.

We claim as our invention:

70 1. In a circuit interrupter comprising a housing of insulating material, barriers at the ends of said housing forming spaced recesses, a terminal mounted in each of

said recesses for connecting said circuit interrupter in an electrical circuit, a separate terminal cover formed from a flat strip of insulating material mounted on said barriers for covering said recesses, said terminal cover having spaced projections thereon engaging means in said recesses for covering the ends of said recesses, and other projections on said separate terminal cover engaging a portion of said interrupter housing to hold said terminal cover in place.

2. In a circuit interrupter comprising an insulating housing, barriers at one end of said housing between them forming spaced recesses, terminals mounted in said recesses for connecting said interrupter in an electrical circuit; a separate terminal guard mounted on said barriers and having spaced projections thereon extending into said recesses, means defining slots in said recesses for receiving said projections and holding said projections in place, said separate terminal guard being bent toward said interrupter housing and having other projections thereon engaging portions of said interrupter housing to firmly hold said separate terminal guard in place.

3. In a circuit interrupter comprising an insulating housing including a base and a cover sealed to said base, said base having at least one end extending beyond the upper portion of said cover, barriers at said end of said housing forming recesses between them, terminals mounted in said recesses to permit connecting said interrupter in an electrical circuit without removing said interrupter cover, a snap-on terminal guard mounted on said barriers, projections on said terminal guard adapted to be inserted into said recesses for covering the ends of said recesses, ribs in said recesses for receiving said projections to hold said projections in place, said terminal guard being bent toward said interrupter housing at right angles to said projections, and other projections on said terminal guard adapted to be engaged with portions of said interrupter housing to hold said terminal guard in place.

4. In a circuit interrupter comprising a housing including a base and a cover sealed to said base, said base having at least one end extending beyond said cover, barriers on said end of said base forming recesses between them, terminals mounted in said recesses to permit connecting said interrupter in an electrical circuit without removing said interrupter cover, and a snap-on terminal guard mounted on said end of said base extending beyond said

cover, projections on said terminal guard adapted to be inserted in said recesses for covering the ends of said recesses, means in said base for receiving said projections, said terminal guard being bent toward said cover at right angles to said projections, and other projections on said terminal guard adapted to engage a portion of said sealed interrupter cover to hold said terminal guard in place without the use of any separate fastening device.

5. In a circuit interrupter comprising a housing including a base and a cover sealed to said base, said base having at least one end extending beyond the upper portion of said cover, barriers at said end of said housing forming recesses between them, terminals mounted in said recesses to permit connecting said interrupter in an electrical circuit without removing said interrupter cover, and a snap-on terminal guard mounted on said end of said base extending beyond said cover, projections on said terminal guard adapted to be inserted in said recesses for covering the ends of said recesses, means defining slots in said base for receiving said projections, said terminal guard after said projections are inserted in said slots being bent toward said cover at right angles to said projections, and other projections on said terminal guard adapted to engage said sealed interrupter cover to hold said terminal guard in place.

6. In a circuit interrupter comprising a housing including a base and a cover sealed to said base, barriers at the end of said housing forming a recess between them, a terminal mounted in said recess to permit connecting said interrupter in an electrical circuit without removing said sealed cover, and a snap-on terminal guard mounted on said barriers, a projection on said terminal guard adapted to be mounted in said recess to cover the end of said recess, means defining a slot in said base for receiving said projection, said terminal guard after said projection is inserted in said slot being bent toward said housing at right angles to said projection, and another projection on said terminal guard adapted to engage a portion of said interrupter housing to hold said terminal guard in place.
